Patent expires April 12, 1958

6 Claims. (Cl. 153—32)

1

The invention relates to a method and also to a device for restoring to shape the walls of deformed sheet-metal boxes and their lids, whereby this work may be performed easily and at low costs.

The method, according to the invention, consists in placing inside the boxes and lids a number of profiling blocks presenting, at their assembled outer periphery, nearly the peripheral shape of a box to be reshaped, subsequently forcing these profiling blocks apart from each other, after which a sleeve or frame, the inner periphery of which corresponds to the normal outer periphery of the box, is slid along the reshaped box, to completely flatten the walls thereof.

A device for carrying out the method according to the invention is characterized in that a number of profiling blocks are so arranged with respect to each other and are so shaped that their assembled outer periphery is nearly equal to the peripheral shape of a box or lid to be reshaped, the profiling blocks presenting, at their adjacent sides or corners, a wedging face, and a wedge being introduced between the profiling blocks and adapted to be moved in the longitudinal direction.

It has been observed that the deformations and torsions imparted to sheet-metal boxes and their lids often increase the volumetric condition of the box or the lid, and the invention provides for eliminating such volumetric deformation by shrinking the area of the walls of the box or the lid, so as to reduce the dimensions of said walls.

The shrinking effect is obtained by stamping ribs or the like irregularities in said walls, and for this purpose use can be made upon the aforementioned device of press-plates having die surfaces cooperating with outer die surfaces provided on the profiling blocks.

The invention will be described hereafter with reference to the accompanying drawing, in which a form of embodiment of the device has been diagrammatically illustrated.

Fig. 1 is a front elevation partly in section of the device for restoring deformed boxes made of sheet-metal.

Fig. 2 is a plan view partially in section and having a top part removed for the purpose of clearness.

On the work-table 1 are arranged four profiling blocks 2 between which can be driven the wedge element 3. Over the profiling blocks 2 is engaged the sheet-metal box to be restored to shape. Around the profiling blocks is arranged a supporting frame 5 formed in two parts. At the

2

inner sides of this supporting frame 5 are mounted four horizontal rollers 6, which are movable in the direction of the profiling blocks, said rollers being permanently under the action of pressure springs 7. Above the profiling blocks 2 is arranged a press-plate 8, the underface of which presents the required irregularities which, in cooperation with die-shaped surfaces of the profiling blocks, will stamp the necessary ribs in the bottom wall of the box or the lid for the purpose of shrinking said wall. The supporting frame 5 is axially movable with respect to the profiling blocks, whereby said frame slides along guiding columns 9. A vertically reciprocating movement is obviously imparted to the press-plate 8 with respect to the profiling blocks.

Similarly, the side walls of the box or the lid may have their area shrunk by stamping ribs therein by means of die plates 8' cooperating with the shaped sides of the profiling blocks.

When the profiling blocks 2, after introduction of the wedge element 3, have been spread apart and the walls of the sheet-metal box 4 have thus been stretched, the pressure rollers 6 are slid by means of their movable frame 5 along the side walls of the box, whereby said side walls become perfectly flattened. During this operation, the upper press-plate 8 will be firmly pressed upon the bottom wall of the box or the top wall of the lid, so that said walls will take the shape stamped therein by the cooperating surfaces of the press-plate and the profiling blocks. Said wall will be shrunk and the side walls may be similarly shrunk by means of the plates 8', the roller frame 5 being obviously lifted at the convenient height. The degree of shrinking of the walls of the box or the lid will be determined by experience and in relation with the ordinary volumetric dimension of the box.

The box and the lid treated according to the invention will have recovered its normal rectangular shape and can be efficiently reused for packing articles, such as biscuits and cakes.

I claim:

1. A device for reshaping sheet-metal boxes and the lids pertaining thereto comprising expandable core means the outer periphery of which is nearly equal to the peripheral shape of the box or lid to be reshaped and said core means being adapted to support said box or lid, and further comprising a supporting frame surrounding the core means and carrying rolls arranged to engage and to exert a pressure on the side walls of the box or lid mounted on the core means, the supporting frame with the rolls and the core

means being slidably arranged with relation to each other.

2. A device for reshaping sheet-metal boxes and the lids pertaining thereto comprising a number of profiling blocks so arranged with respect to each other and so shaped that their assembled outer periphery is nearly equal to the peripheral shape of the box or lid to be reshaped, said profiling blocks having a wedging plane at their sides facing each other, a wedge element adapted to be moved between the profiling blocks in engagement with the wedging planes thereof, a supporting frame surrounding the profile blocks, rolls mounted in said frame arranged to engage and to exert a pressure on the side walls of a box or lid mounted on the profile blocks, the supporting frame and the profiling blocks being slidably arranged with relation to each other.

3. A device for reshaping sheet-metal boxes and the lids pertaining thereto, comprising a number of profiling blocks so arranged with respect to each other and so shaped that their assembled outer periphery is nearly equal to the peripheral shape of the box or lid to be reshaped, said profiling blocks having a wedging plane at their sides facing each other, a wedge element adapted to be moved between the profiling blocks in engagement with the wedge planes thereof, a supporting frame surrounding the profile blocks, rolls mounted in said frame arranged to engage and to exert a pressure on the side walls of a box or lid mounted on the profile blocks, the supporting frame and the profiling blocks being slidably arranged with relation to each other, and a press-plate adapted to press the bottom wall of the box or the top wall of the lid against the adjacent side of the profile blocks.

4. A device for reshaping sheet-metal boxes and the lids pertaining thereto, comprising a number of profiling blocks so arranged with respect to each other and so shaped that their assembled outer periphery is nearly equal to the peripheral shape of the box or lid to be reshaped, said profiling blocks having a wedging plane at their sides facing each other, a wedge element adapted to be moved between the profiling blocks in engagement with the wedging planes thereof, a supporting frame surrounding the profile blocks, rolls mounted in said frame arranged to engage and to exert a pressure on the side walls of a box or lid mounted on the profile blocks, the supporting frame and the profiling blocks being slidably arranged with relation to each other, and a press-plate adapted to stamp ribs in the bottom wall of the box or the top wall of the lid, the adjacent side of the profiling blocks and of the pressure plate forming dies for this purpose.

5. A device for reshaping sheet-metal boxes

and the lids pertaining thereto, comprising a number of profiling blocks so arranged with respect to each other and so shaped that their assembled outer periphery is nearly equal to the peripheral shape of the box to be reshaped, said profiling blocks having a wedging plane at their sides facing each other, a wedge element adapted to be moved between the profiling blocks in engagement with the wedging planes thereof, a supporting frame surrounding the profiling blocks, spring pressed rolls mounted in said frame arranged to engage and to exert a pressure on the side walls of the box or lid mounted on the profiling blocks, the supporting frame and the profiling blocks being slidably arranged with relation to each other, and a press-plate adapted to press the bottom wall of the box or the top wall of the lid against the adjacent side of the profiling blocks.

6. A device for reshaping sheet-metal boxes and the lids pertaining thereto, comprising a number of profiling blocks so arranged with respect to each other and so shaped that their assembled outer periphery is nearly equal to the peripheral shape of the box to be reshaped, said profiling blocks having a wedging plane at their sides facing each other, a wedge element adapted to be moved between the profiling blocks in engagement with the wedging planes thereof, a supporting frame surrounding the profiling blocks, spring pressed rolls mounted in said frame arranged to engage and to exert a pressure on a box or lid mounted on the profiling blocks, the supporting frame and the profiling blocks being slidably arranged with relation to each other, and press-plates adapted to stamp ribs in the walls of the box or the lid to be reshaped, the adjacent sides of the profiling blocks and of the pressure plates forming dies for this purpose.
